ELOF MEDEN, OF TRENTON, NEW JERSEY, ASSIGNOR TO THE JEANESVILLE IRON WORKS COMPANY, OF HAZLETON, PENNSYLVANIA, A CORPORATION OF PENNSYLVANIA.

CENTRIFUGAL PUMP.

No. 851,364.

Specification of Letters Patent.

Patented April 23, 1907.

Application filed April 6, 1905. Serial No. 253,979.

To all whom it may concern:

Be it known that I, ELOF MEDEN, a subject of the King of Sweden, residing in the city of Trenton, in the county of Mercer, State of New Jersey, have invented certain new and useful Improvements in Centrifugal Pumps, of which the following is a specification.

My invention relates more particularly to multistage or compound centrifugal pumps, and the main object of my invention is to provide an efficient means whereby end thrust and its variations in the running of the pump may be counterbalanced.

The figure in the accompanying drawings is a longitudinal section of a multistage or compound centrifugal pump provided with my invention. In this instance I have illustrated the pump as constructed with four stages, but it will be understood that more or fewer may be employed as desired.

The runners or impellers, which are marked A, A', A², A³, are mounted upon the main shaft S so as to turn therewith, and this shaft 25 runs in bearings B, B', carried by the casing C. The suction inlet for the water is at D and the outlet is at the opposite end of the casing as indicated by the dotted circles E in the figure.

Between the impellers or runners A, A', are the series of stationary partitions G and H, forming channels F, F', F², leading from the periphery of one impeller to near the hub of the next, as usual. The partition G between each impeller (A for example) and the succeeding set of channels (F), preferably, extends down to the hub of the next following impeller (A'), so that each impeller has all its effective parts running within its own 35 chamber a. The pressure in each chamber a in which an impeller runs is approximately that at the point where that impeller discharges its water at its periphery, and as that is greater than at the point where the water 40 enters that impeller, it follows that there will be an excess of pressure on the far side or left hand side (in the drawing) of each impeller, except in the case of the last impeller A³, as I will describe. I counterbalance or counteract the accumulated excess of end thrust on 45 all the impellers by the means to be now described.

I form or secure in the inner face of the rear

end of the casing C a hollow ring J of a diameter, which may conveniently be about equal 55 to the diameter of the ring face of the admission side of impeller A³, where it projects through the partition H. An annular flange a² on the adjacent face of this impeller forms a lap joint with the forward face of this ring 60 J, so that these two parts form the three sides of a chamber K, whose fourth side is closed by the shouldered end or plug P of a sleeve O, which is mounted on and turns with the shaft S. This sleeve has a screw thread connection 65 with the shaft at x so that by turning the sleeve on the shaft, the sleeve and its shouldered or plug end can be adjusted on the shaft; and this can be done from the outside of the casing for the sleeve projects through a stuff- 70 ing box R in the end of the casing. A lock nut p may be used to lock the sleeve in its adjusted position.

Back of the chamber K is a chamber M, which may be at all times in communication 75 with the suction of the pump through a channel N in the casing.

If during the operation of the pump, there is end thrust to the left, the plug P being fixed on the shaft will move to the left and close 80 and trap the water in the chamber K, and this trapped body of water will take the end thrust.

If there is end thrust to the right from excess of pressure in the chamber K, due to accumulation of leakage of water into it from the chamber in which the last impeller runs; the shaft will carry the plug P to the right 85 sufficiently to momentarily open the chamber K to the chamber M, and so allow the excess 90 to escape from the chamber K. The passage N to the suction affords a convenient channel for carrying off these intermittent discharges of excess pressure from chamber K.

I prefer to form the sleeve O of phosphor 95 bronze, so that in addition to the fact that it enables the plug P to be adjusted readily from outside the casing, it may protect the shaft from the action of acidulous water when the pump is used in mines or elsewhere. 100

I claim as my invention

1. In a multistage centrifugal pump, the combination of a casing, a shaft, a series of impellers on the shaft and a chamber at the delivery end of the casing, open to a part of 105 the rear face of the last impeller with a sleeve

secured on the shaft extending to the outside of the casing and on the inside providing a plug to open or close said chamber by longitudinal movement of the shaft.

- 5 2. In a multistage centrifugal pump, the combination of a casing, a shaft, a series of impellers on the shaft and a chamber at the delivery end of the casing open to a part of the rear face of the last impeller with a sleeve
10 secured to and adjustable on the shaft and extending to the outside of the casing and on

the inside providing a plug to open or close said chamber by longitudinal movement of the shaft.

In testimony whereof I have signed my name to this specification, in the presence of two subscribing witnesses.

ELOF MEDEN.
